UNITED STATES PATENT OFFICE.

PHILIP S. MEDART AND FRANK ALBACH, OF ST. LOUIS, MISSOURI, ASSIGNEES TO FRED MEDART MANUFACTURING COMPANY, OF ST. LOUIS, MISSOURI, A CORPORATION OF MISSOURI.

EXERCISING APPARATUS.

Application filed May 12, 1921. Serial No. 468,838.

To all whom it may concern:

Be it known that we, PHILIP S. MEDART and FRANK ALBACH, citizens of the United States of America, and residents of the city 5 of St. Louis, State of Missouri, have invented certain new and useful Improvements in Exercising Apparatus, of which the following is a specification.

This invention relates to inter-connected 10 means for effecting a ready and substantial adjustment of the upper or body member of a vaulting horse or like gymnasium apparatus in a vertical plane, and for operating the caster mechanism of such apparatus from a 15 dormant to an active position and vice versa, and the present improvement has for its object:—

To provide a structural formation and 20 combination of parts and mechanisms by means of which a ready shifting of a single driving mechanism can be effected to attain the required vertical adjustment of the body member of the apparatus, or a movement of the caster mechanism from its 25 active to an active position, in moving the apparatus from one location to another, all as will hereinafter more fully appear.

In the accompanying drawings:—

Fig. 1, is a longitudinal sectional elevation 30 of a vaulting horse, illustrating the general arrangement of parts in the present invention.

Fig. 2 is an enlarged detail section on line 2—2, Fig. 3 of the primary operating 35 mechanisms.

Fig. 3 is a similar transverse section on line 3—3 Fig. 2.

Fig. 4 is a similar transverse section on 40 line 4—4, Fig. 2.

Fig. 5 is a detail central longitudinal section on line 5—5, Fig. 4 of the secondary operating mechanism, and also showing the associated caster mechanism.

Fig. 6 is a detail section at right angles to 45 Fig. 4, illustrating said caster mechanism.

Like reference numerals indicate like parts in the several views.

Referring to the drawings, 1 and 2 designate the respective tubular columns of a 50 vaulting horse, rigidly connected to the floor plate or rest 3 as usual, with the vertical

bores of said columns formed as guides for the vertically adjustable tubular posts of the body of the vaulting horse now to be described.

4 designates the horse body of the usual hollow open bottom construction and from which depend tubular posts 5 adapted for vertical adjustment in the columns 1, 2, aforesaid. In the present construction said 60 body is formed with a passage 4' for the purpose hereinafter set forth.

In the present improvement the upper and attaching ends of the posts 5 are formed with enlarged casings or housings 5' adapted to enclose and provide bearings for the hereinafter described gearing by which the adjusting means of the body are operated.

6 designates sleeves or tube sections, revolvably mounted in bearings 6' in the posts 70 5 so as to have vertical travel in unison therewith. Said sleeves are formed with screw threaded bores for operative engagement with the hereinafter described centrally arranged spindles.

7 designates gear wheels fixed on the upper ends of the sleeves 6 to constitute part 75 of the gearing by which rotation is imparted to the sleeves.

8 designates vertical shafts or spindles of a telescoping form arranged axially in the sleeves 6 and associated posts 5, and journaled so as to be capable of semi-rotary movement in lower bearings 9 and upper bearings 10. Each of said upper bearings 80 is preferably formed by a center screw 10 turning in a horizontal bridge rail 10' in an enlarged casing 5' aforesaid. The shafts or spindles 8 are formed with screw threaded portions near their lower ends for operative engagement with the screw threaded portions of the bores of the sleeves 6, and so that with the rotation of the sleeves 6, the same will have vertical movement and will carry the posts 6 and horse body 4 in an 85 upward or a downward direction in accordance with the directions in which said sleeves are rotated. In such operation the screw threaded shafts 8 are held from rotation with the sleeves 6 by their operative connection with the caster operating means of 90 the apparatus.

11 designates gear wheels fixed on the upper ends of the shafts 8 to constitute parts of the gearing by which rotation is imparted to said shafts.

5 The caster mechanisms above referred to, each comprise caster wheels 12, the carrying frame 13 of which is arranged below the lower end of the aforesaid shaft 8 and is adapted to receive a transverse movement 10 from said shaft through an operative connection hereinafter described, and such transverse movement of the frame 13 is converted into a vertical movement thereof by links 14 or other equivalent means, interposed between the upper face of the frame 13 and the opposed face of the open bottom recess in the floor plate or base 3 in which an individual caster mechanism is arranged as illustrated in Figs. 5 and 6.

20 15 designates a crank arm fixedly connected to the lower end of the aforesaid vertical shaft 8 and having a crank pin 15' adapted for operative engagement in a longitudinal slot 18' in the mid-portion of the frame 13, so as to impart the above mentioned simultaneous transverse and vertical movements to said frame on a partial rotation of the shaft 8, to move the caster wheels from a normal inactive position into an active position and vice versa.

25 16 designates a shaft extending between and journalled in the casings 5, aforesaid, and carrying gear wheels 17 which gear with the gear wheels 7 of the sleeves 6 to impart simultaneous rotation to the same.

30 18 designates a companion shaft extending between and journalled in the aforesaid casings 5, and carrying gear wheels 19 which gear with the gear wheels 11 of the central shafts 8 to impart simultaneous rotation thereto.

35 The pairs of gear wheels 7, 17 and 11, 19, above described, are preferably of the ordinary spiral type shown, but may be of the ordinary bevel type if so desired.

40 20 designates a gear wheel fixed on one end of the shaft 16, and arranged within a casing 5, while 21 designates a similar gear wheel fixed on the end of the companion shaft 18 and arranged in a longitudinal plane a distance removed from the gear wheel 20, as shown in Fig. 2, and for the purpose hereinafter set forth.

45 22 designates an idler gear wheel having operative engagement with the gear wheel 21 and adapted in turn for operative engagement with the change gear wheel now to be described.

50 23 designates a longitudinally shiftable sleeve revolvably mounted in a bearing orifice in the casing 5 in which it slides. The sleeve 23 is also supported on a tubular housing 24 and has key and keyway connection therewith so that the two parts will turn in

unison while permitting the sleeve 23 to have 65 the described sliding movement.

25 designates a head or handle on the exterior of the sleeve 23 for effecting a convenient manual shifting of said sleeve.

26 designates a change gear wheel 70 secured to one end of the sleeve 23, and adapted in accordance with the position to which said sleeve is shifted, to engage one or the other of the gear wheels 20, 22, above described.

27 designates a non-circular shaft fitting the correspondingly formed bore of the aforesaid supporting housing 24. Said shaft 27 is of greater length than said supporting housing 24 so as to be capable of longitudinal movement in said housing and is provided with an operating hand crank 28 at one end and with a stop collar 29 at the other end, to limit its independent adjustment in either direction. 75

With the described construction the shaft 27 in its inactive condition is wholly within the hollow of the horse body 4 and is enclosed and protected from accidental contact as illustrated in Fig. 1. When required 80 for active use the shaft 27 is pulled out longitudinally through the passage 4' of the horse body in order that said hand crank 28 will be clear of the end of said horse body for convenient manual operation. When the present improvements are applied to a vaulting buck or like exercising apparatus in which a single supporting column is only used, the parts will be modified accordingly 85 by the omission of the mechanisms and mechanisms of the secondary column 2 above described.

90 Having thus fully described our invention what we claim as new and desire to secure by Letters Patent, is:—

1. In an exercising apparatus, a base, a hollow body supported in a vertically adjustable manner on said base, means for imparting vertical adjustment to said body, a longitudinally arranged housing having operative engagement with said adjusting means, and a non-circular shaft arranged in a longitudinally adjustable manner in said housing and having an operative crank at one end, said shaft being adapted to be moved from an inactive position in the hollow body into an active position outside said body, said body having a passage in an end wall for such movement of the shaft. 100

110 2. In an exercising apparatus, a base provided with a vertically adjustable caster mechanism, a body supported in a vertically adjustable manner on said base, means for imparting vertical adjustments to said caster mechanism and to said body, the same comprising driven gear wheels associated with said adjusting means and arranged out of alignment one with the other, a driving gear 115

wheel capable of a shifting movement to engage one or the other of said driven wheels, manual means for shifting said driving gear wheel, and manual means for imparting rotation to said driving gear wheel.

3. In an exercising apparatus, a base provided with a vertically adjustable caster mechanism, a body supported in a vertically adjustable manner on said base, means for imparting vertical adjustments to said caster mechanism and to said body, the same comprising driven gear wheels associated with said adjusting means and arranged out of alignment one with the other, a driving gear wheel capable of a shifting movement to engage one or the other of said driven gear wheels, and a longitudinally slidable crank shaft operatively engaging said driving gear wheel and adapted to be moved to an operative position beyond the end of the body.

4. In an exercising apparatus, a base provided with a vertically adjustable caster mechanism, a hollow body supported in a vertically adjustable manner on said base, means for imparting vertical adjustments to said caster mechanism and to said body, the same comprising driven gear wheels associated with said adjusting means and arranged out of alignment one with the other, a driving gear wheel capable of a shifting movement to engage one or the other of said driven gear wheels, and a longitudinally slidable crank shaft operatively engaging said driving gear wheel and adapted to be moved to an operative position beyond an end of the body through a passage in an end wall of the same.

5. In an exercising apparatus, a base having a tubular column, a body provided with a depending tubular post guided vertically in said column and having at its upper end a hollow housing, a sleeve revolvably mounted in said post and having a screw threaded bore, a gear wheel secured to the upper end of said sleeve, a centrally arranged shaft attached at its lower end to the aforesaid column and having screw threaded engagement with the sleeve aforesaid, a shaft carrying a gear wheel meshing with the gear wheel of the aforesaid sleeve and with a second gear wheel acting as a driven member, and a longitudinally slidable crank shaft operatively engaging said driving gear wheel and adapted to be moved to an operative position beyond the end of the body.

6. In an exercising apparatus, a base having a tubular column, a body provided with a depending tubular post guided vertically in said column and having at its upper end a hollow housing, a sleeve revolvably mounted in said post and having a screw threaded bore, a gear wheel secured to the upper end of said sleeve, a centrally arranged shaft of a telescoping form attached at its lower

end to the column and at its upper end to said post, said shaft having screw threaded engagement with the sleeve aforesaid, a shaft carrying a gear wheel meshing with a gear wheel of the aforesaid sleeve and with a second gear wheel acting as a driven member, a driving gear wheel engaging said driven gear wheel, and a longitudinally slidable crank shaft operatively engaging said driving gear wheel and adapted to be moved to an operative position beyond the end of the body.

7. In an exercising apparatus, a base having a tubular column, a body provided with a depending tubular post guided vertically in said column and having at its upper end a hollow housing, a sleeve revolvably mounted in said post and having a screw threaded bore, a gear wheel secured to the upper end of said sleeve, a centrally arranged shaft journaled in the aforesaid column and having screw threaded engagement with the bore of the aforesaid sleeve, a driven gear wheel on the upper end of said shaft, a vertically adjustable caster mechanism arranged in a recess on the under side of the base and operatively connected to said shaft, a pair of counter shafts journaled in the hollow housing of the post, one of said counter shafts having a gear wheel in driving engagement with the gear wheel of the aforesaid central shaft and an additional gear wheel acting as the driven member of said counter shaft, the other of the counter shafts having a gear wheel in driving engagement with the gear wheel of the aforesaid sleeve and an additional gear wheel acting as the driven member of said countershaft, said additional gear wheels of the countershafts being disposed in separated longitudinal relation, a driving gear wheel capable of a shifting movement to engage one or the other of said additional gear wheels, and an operating crank shaft carrying said driving gear wheel.

8. In an exercising apparatus, a base having a tubular column, a body provided with a depending tubular post guided vertically in said column and having at its upper end a hollow housing, a sleeve revolvably mounted in said post and having a screw threaded bore, a gear wheel secured to the upper end of said sleeve, a centrally arranged shaft of a telescoping form attached at its lower end to the column and at its upper end to said post, said shaft having screw threaded engagement with the sleeve aforesaid, a driven gear wheel on the upper end of said shaft, a vertically adjustable caster mechanism arranged in a recess on the underside of the base and operatively connected to said shaft, a pair of countershafts journaled in the hollow housing of the post, one of said countershafts having a gear wheel in driving engagement with the gear

wheel of the aforesaid central shaft and an additional gear wheel acting as the driven member of said countershaft, the other of the countershafts having a gear wheel in driving engagement with the gear wheel of the aforesaid sleeve and an additional gear wheel acting as the driven member of said countershaft, said additional gear wheels of the countershafts being disposed in sepa-

rated longitudinal relation, a driving gear 10 wheel capable of shifting movement to engage one or the other of said additional gears, and an operating crank carrying said driving gear wheel.

Signed at St. Louis, Missouri, this 9th day of May 1921.

PHILIP S. MEDART.
FRANK ALBACH.
